[57] **CLAIM**

The ornamental design for an audio speaker cabinet, as shown and described.

DESCRIPTION

FIG. 1 is a front, top and right side isometric view of an audio speaker cabinet showing my new design, the left side view being a mirror image of the right side view;

FIG. 2 is a front view thereof;

FIG. 3 is a sectional view taken along the lines 3—3 of FIG. 2; and,

FIG. 4 is a sectional view taken along the lines 4—4 of FIG. 2.

The broken line showing of the speakers is for illustrative purposes only and forms no part of the claimed design.
